PHONOGRAPH

Louis Z. La Forest, Orange, N. J., assignor to
 Thomas A. Edison, Incorporated, West Orange,
 N. J., a corporation of New Jersey

Application November 12, 1938, Serial No. 239,953

5 Claims. (Cl. 274—17)

This invention relates to phonographs, and more particularly to phonographs of the type which comprise a speaking tube, or the like, for conveying sound to and from the machine.

Phonographs of the abovementioned type are commonly employed for the recordation and reproduction of dictation, and are known as "dictating machines." These machines comprise means for rotating a record and a record-cooperating sound translating device usually at least partially overlying the record. To this translating device there is coupled a speaking tube having a handpiece, or sound-receiving device, at its outer end adapted to be grasped by the hand during the use of the machine, the speaking tube being usually flexible and of such length as to permit freedom of movement to the operator during the use of the machine. For convenience in the operation of the machine, it is important that the point at which this speaking tube extends from the machine be carefully chosen so that the tube will not obstruct such access to the machine as is necessary to its operation; it is further important, particularly in machines which are intended for use on desks or tables, that the arrangement of the phonograph and cabinet be highly compact and yet provide sufficient space for the storing of the speaking tube during the non-use of the machine.

It is an object of my invention to provide an arrangement of phonograph and cabinet fulfilling the important requirements, as noted above.

It is another object to provide a cabinet closely fitting a complete phonograph, which is openable by a single manipulation, to expose the phonograph for immediate operation.

It is another object of my invention to locate the speaking tube so that, during the use of the machine, it will not hinder or obstruct access to manipulative parts of the machine.

It is another object of my invention to provide, in a compact arrangement of a complete phonograph and a cabinet therefor, a compartment beneath the phonograph for the storing of the speaking tube during the non-use of the machine.

It is a further object of my invention to couple the sound translating device to the speaking tube by means of a sound tube partially surrounding the record rearwardly thereof.

It is another object of my invention to provide a movable support in the abovementioned compartment for the handpiece of the speaking tube, which is automatically moved into an upper supporting position rendering the handpiece readily accessible upon opening the cabinet and into a lower supporting position upon closing the cabinet.

A further object of my invention is to provide improved means for automatically starting the machine as an incident of removing the hand-

piece from its support while the support is in its upper supporting position.

Other objects of my invention will more fully appear from the following description and the appended claims.

In the description of my invention reference is had to the accompanying drawings, of which:

Fig. 1 is a top plan view of a phonograph and cabinet in accordance with my invention, the top of the cabinet being removed for the better illustration of the phonograph;

Fig. 2 is a vertical cross sectional view of the phonograph and cabinet in accordance with my invention, taken substantially along the line 2—2 of Fig. 1, but showing the speaking tube in elevation;

Fig. 3 is a fragmentary vertical cross sectional view taken substantially along the line 3—3 of Fig. 1;

Fig. 4 is a right side elevational view of the cabinet of the above figures, a side wall portion of the cabinet being broken away for the better illustration of parts therebehind;

Fig. 5 is a fragmentary sectional view taken substantially along the line 5—5 of Fig. 4;

Fig. 6 is principally a left hand elevational view of mechanism operated by the cover or main closure, the cover being in open position;

Fig. 7 is a vertical cross sectional view of the mechanism shown in Fig. 6, taken substantially along the line 7—7 of Fig. 1; and

Fig. 8 is a detailed view of a portion of the mechanism of Fig. 6, taken substantially along the line 8—8 of Fig. 6.

Reference being had to Figs. 1 and 2, there will be seen a cabinet 1 having a lower portion 2 which is substantially rectangular in cross section as viewed from the top, and a top portion, which is substantially arcuately shaped as viewed from the end, the top portion comprising a rearward section 3 and a front closure or cover 4. The cabinet 1 contains a phonograph arranged in accordance with my invention, having a frame or base 6 carrying the various parts of the phonograph. The lower cabinet portion 2 supports the base 6 in a position at the level of the top of that portion, the base being supported at its front by a bracket 7, which is secured to the forward wall of the lower cabinet portion 2, and at its rear by left and right brackets 8 and 9 secured to the rearward wall of the cabinet portion 2 and respectively pivotally connected by shoulder screws 8' and 9' to left and right rearwardly extending arms 10 and 11 provided on the base.

The phonograph has its principal parts disposed at, or above, the general level of the base 6 in order to form a compartment 12 beneath the base in the lower cabinet portion 2. The phonograph parts which are disposed above the base 6 are carried principally by an intermediate up-

right standard 13 and by left and right upright standards 14 and 15 of the base 6. In the intermediate standard 13 there is journaled a shaft 16 having a mandrel 17 to the right of the standard for removably carrying a cylindrical record 18. The portion of the base 6 which lies along the record 18—i. e., the portion lying to the right of the intermediate standard 13—comprises a raised portion in the form of a platform 19 disposed behind the record and curving downwardly about the record to form an arcuate portion 20. Extending forwardly from the arcuate portion 20 is a flat downwardly inclined base portion 21 having a relatively large laterally extending opening 22 exposing the interior of the compartment 12. The portion 21 terminates along its forward edge in a vertically extending reenforcing rib 23 which normally rests on the bracket 7. The rib 23 is integral with left and right vertically disposed side ribs 24 and 25 (see Figures 6 and 7) which extend from front to back along the side edges of the base 6 and terminate in the left and right arms 10 and 11. The left side rib 24 has a downwardly curved central portion 24' which is offset to the right to provide space to the left thereof for mechanism hereinafter described, the portion 24' also serving as a support for parts of the phonograph.

Supported by the left and right standards 14 and 15 are the front and back longitudinal rods 30 and 31. Slidably mounted on these rods is a carriage 32 having a sleeve 33' embracing the rod 30. The carriage 32 is provided with a forwardly extending arm 32' overlying the record 18 and carrying a sound translating device 33 adapted to cooperate with the record. Advancing movement of the translating device 33 from a start position to other positions across the record 18, coincidental with a rotation of the mandrel 17, is effected by a driving means comprising a feed screw 34 rotatably supported by the left and right standards 14 and 15 and geared to the mandrel shaft 16 by a train of gears 35, of which the intermediate gear 35' is pivoted on a rearward extension 13' of the intermediate standard 13. Movable into and out of engagement with the feed screw 34 is a feed nut 36 secured to a bracket 37 pivoted to the carriage by a pivot rod 38. When the feed nut 36 and feed screw 34 are engaged a steady rotation of the feed screw will cause the translating device 33 to be steadily advanced relative to the record, but when the feed nut and feed screws are disengaged either the carriage arm 32' or the translating device carried thereon may be grasped by the hand and manipulated across the record at will, such manipulation being particularly relied upon for the return of the translating device to start position.

The driving means for the mandrel and carriage may comprise a suitable electrical motor 39 preferably located in the rearward part of the cabinet 1 between the left and right arms 10 and 11 of the base 6. The motor 39 has a drive pulley 40 coupled by a belt 40' to a pulley 41 rotatably mounted on the standard 14 with its axis in line with the mandrel shaft 16. The pulley 41 is coupled at will with the mandrel shaft 16 by means of a clutch 42 comprising a toothed circular member 43 suitably splined to the mandrel shaft 16 and movable into and out of engagement with another toothed circular member 44 provided on the pulley 41. For moving the member 43 leftwardly and rightwardly on the mandrel shaft 16 to effect the engagement and disengage-

ment of the clutch 42 there may be provided a movable control member 45 carrying a pin 46 engaging an annular groove 47 in the clutch member 43.

5 In order that a belt may freely pass from the drive pulley 40 to the driven pulley 41 there is provided between the left standard 14 and the intermediate standard 13 a rearwardly extending channel 48. The bottom 49 of the channel is on 10 a level with the lowest part of the arcuate portion 20 of the base; the left side of the channel is formed by the standard 14; and the right side of the channel is formed in part by the intermediate standard 13, in part by the rearward 15 extension 13' of this standard, and otherwise by a wall 50 which extends rearwardly of the extension 13' between the platform 19 and the bottom 49 of the channel.

The sound translating device 33 may have an 20 inoperative condition and respective operation conditions for recording and reproducing. When conditioned for recording, the translating device is adapted to receive sound waves and impart a movement undulating in accordance with those 25 waves to a recorder stylus 51 which, when in contact with a rotating record, forms a progressive modulated groove thereon, and, when conditioned for reproducing, to create sound waves in accordance with any undulating movement imparted to a reproducer stylus 52, as by the engagement of the reproducer stylus with a progressive modulated groove on the record 18.

The translating device may be shipped between 30 inoperative and operative conditions at will and 35 may be manipulated across the record when the feed nut 36 is disengaged from the feed screw 34 as is hereinbefore described. The means for shifting the translating device between inoperative and operative conditions, and for controlling the engagement of the feed nut 36 with the feed screw 34, comprises a forwardly extending control or shifting lever 53 which is pivoted by a pivot screw 54 on a boss 54' provided on the right side of the carriage arm 32'. The control 40 lever 53 has a short downwardly extending arm 55 pivoted by a pin 55' to a link 56 which in turn is pivoted by a pin 56' to a block-shaped member 57 pivotally mounted on the sleeve 33' within the hub portion 32'' of the carriage 32. Upward and 45 downward rocking movement of the lever 53 from its intermediate position shown in Fig. 2 thus causes clockwise and counterclockwise angular movements of the member 57. The condition of the translating device and the position of the feed nut 36 relative to the feed screw 34 are controlled in accordance with the angular positioning of the member 57 by a mechanism not herein necessary to show. When the control lever 53 is in its 50 intermediate position the feed nut 36 is out of engagement with the feed screw 34 and the translating device is in an inoperative condition, the recorder and reproducer styli 51 and 52 each being then in a raised position free of the record 18; when the control lever 53 is moved upwardly 55 from its intermediate position the feed nut 36 is brought into engagement with the feed screw 34 and the translating device 33 is placed in a condition for reproducing, the reproducer stylus 52 then being in engagement with the record 18; and when the control lever 53 is moved downwardly from its intermediate position the feed nut 36 is again brought into engagement with the feed screw 34 but the translating device is 60 placed in a condition for recording, the recorder

stylus 51 then being in engagement with the record 18.

To facilitate the mounting of a record on, and its removal from, the mandrel 17 there is provided a record ejector, preferably of the type disclosed in Gramann Patent No. 2,010,717, issued on August 6, 1935, and entitled "Phonograph." This record ejector may be sufficiently described in the present instance by the following statements: The ejector comprises a disc-shaped member 26 biased rightwardly and arranged to abut against the left end of the record. At the free end of the mandrel there is provided an expandable and contractible chuck 27 biased into an expanded position but adapted to be held in a contracted position and to be released therefrom by a leftward movement of the disk member 26. When a record is mounted on the mandrel the disk member 26 is moved leftwardly to release the chuck 27 and the chuck 27 then expands to hold the record on the mandrel. To eject the record the chuck 27 is contracted by imparting an inward movement to a manually operable control 28 carried by the mandrel at the free end thereof. When the chuck is contracted, the record is ejected by the rightwardly biased disk member 26, the chuck then being again releasably held in a contracted position.

Whenever a record is to be mounted on or removed from the mandrel 17 the free end of the mandrel must be fully exposed. For this reason the pivoting of the cover 4 at its right side must be effected by a pivoting means which will not obstruct the free end of the mandrel. Such pivoting may be effected by an arcuate member 58 (see Fig. 4) provided with a longitudinally extending channel 59 facing to the right and having a longitudinal slot 60 extending substantially throughout the length thereof. The arcuate member 58 is slidably supported by and effectively pivoted to the right standard 15 by means of the upper and lower headed screws 65 and 66 which pass through the slot 60, thread into the standard, the respective heads 65' and 66' of these screws being disposed within the channel 59. Extending throughout the length of the arcuate member are inner and outer strips 61 and 62; along the forward portion of the member 58 the strips 61 and 62 are each secured, as by welding, to the right end wall 63 of the cover 4; but at an intermediate point 64 along the member 58 (see Fig. 5) the strips 61 and 62 are each offset to the left away from the end wall 63 to provide a clearance, as is hereinafter described.

The left side of the cover 4 is pivoted to the left standard 14, as shown in Fig. 1 and 6, by means of an arm 65 which is secured as by welding to a left end wall 66 of the cover and pivoted to a leftwardly extending boss 67 on the standard 14 by a pivot screw 68. The inner edge 66' of the end wall 66 is curved in an arc about the pivot screw 68. The central portion of the lefthand end wall of the cabinet is not closed by the cover 4 and the rearward section 3. For this portion there may be provided a closure 69 bent inwardly to form a guard or front closure 69' for the pulley 41 and clutch 42, the front closure 69' being shaped to conform with the edge 66' of the left end wall 66 of the cover 4.

The open and closed positions of the cover 4 are respectively shown in Figs. 6 and 2. The opening of the cover 4 is adapted to provide such access to the front portion of the phonograph as is necessary to its operation. The movement of the cover 4 from closed to open position is,

however, insufficient in itself to fully expose the free end of the mandrel 17. For this reason, the free end of the mandrel 17 is closed partially by the righthand end wall 63 of the cover 4 when the cover is in closed position and otherwise by a separate side closure 70 for the cabinet, as is disclosed in my Patent No. 2,203,096 issued June 4, 1940. The closure 70 is provided with a supporting arm 71 lying adjacent to the inner surface of the wall 63 and pivoted thereto by a pivot screw 72; it is for the purpose of clearing the arm 71 that the arcuate member 58 is offset at 64, as is aforementioned. This supporting arm is offset to the right along the line 73 to permit the closure 70 to be in substantial alignment with the end wall 63 of the cover, the upper edge 70' of the closure 70 being shaped to conform with the inner edge 63' of the end wall 63. To reinforce the connection of the closure 70 to the cover 4, the arm 71 is provided with a slot 74, curved in an arc about the pivot screw 72, through which slidably passes a headed pin 75 secured, as by riveting, to the end wall 63. Thus the side closure 70 is carried by, and movable relatively to, the cover 4.

A movement of the side closure 70 relative to the cover, such as is necessary to effect the open and closed positions of the side closure, is adapted to occur as an incident of opening and closing the cover 4. Reference being had to Fig. 4 it will be seen that when the cover 4 is closed the side closure 70 is urged by gravity into its closed position. As the cover 4 is opened the side closure 70 is urged by gravity in a counterclockwise direction relative to the cover, into its open position, shown in dash-dot lines in Fig. 4 and defined by the contact of the pin 75 in the forward end of the slot 74. In order, however, to insure the positive opening and closing of the side closure 70 coincidentally with the opening and closing of the cover 4, the supporting arm 71 is provided with an upward extension 76 and on the standard 15 there are provided the brackets 77 and 78, secured to the standard by the screws 77' and 78', which respectively lie in the terminal positions of the path of the extension 76. As the cover 4 nears its open position, the extension 76 impinges upon the bracket 77 to cause the side closure 70 to be positively moved into open position; and when the cover 4 nears its closed position the extension 76 impinges upon the bracket 78 to cause the side closure to be positively moved into closed position.

In the operation of the machine, sound is conveyed to the translating device 33 during recording and from the translating device during reproducing. For conveying the sound to and/or from the translating device there is provided a flexible sound-conveying tube 79, commonly known as a speaking tube, having a handpiece or sound-receiving device 80 at its outer end usable as a mouthpiece during recording and as an earpiece during reproducing. The handpiece 80 usually carries a suitable control means for the phonograph, not herein necessary to show, operable by moving a plate or cover 81 inwardly as by a grasp of the hand, this control means being connected with the phonograph by a cable 82 which may pass within and along the tube and extend therefrom as through a vent 83.

The speaking tube 79 has a considerable size, having a substantial diameter to permit efficiency in sound conveyance and a substantial length to permit freedom of movement to the operator during the use of the machine. Because of this size of the speaking tube there is encountered,

particularly in compactly arranged machines adapted for use on desks or the like, a difficult problem in finding sufficient space for the storing of the tube during the non-use of the machine. Furthermore, if the speaking tube is directly connected to the translating device it may obstruct such access to the translating device 33 or carriage 32 as is necessary for manipulation to move the translating device across the record, or it may obstruct access to manipulative means in the vicinity of the translating device such, for example, as the control lever 53 heretofore described, or a marking guide 84 carried by the carriage arm 32' (see Fig. 2) along which a pencil may be manipulated to mark an index slip S to indicate positions of the carriage in its travel along the record, (the index slip S being for example held in an index slip holder 85 secured to the forward portion 2 of the base 6 by the screws 86). In accordance with my invention, I provide the compartment 12 beneath the phonograph for the storing of the speaking tube 79 and handpiece 80, which compartment is relatively flat so as not to substantially increase the overall height of the machine; I further couple the speaking tube 79 to the translating device 33 by means of a sound tube 87 extending rearwardly from the translating device and downwardly behind the record 13 into the compartment 12. When the machine is used, the handpiece 80 is taken out of the compartment by way of the opening 22; the speaking tube then extends outwardly from a lower portion of the machine leaving the upper portion of the machine, wherein the abovementioned manipulative means are located, freely accessible. Moreover, since in this arrangement the speaking tube does not obstruct the translating device forwardly thereof, the cover 4 may be placed immediately adjacent to the translating device so as to render it readily accessible when the cover is open.

The sound tube 87 is secured to the translating device 33 by means of an annular coupling 88 and is disposed rearwardly of the translating device, the tube passing over and behind the longitudinal rod 39 and terminating at a point behind the record 18. On the left side of the carriage 32 behind the record 18 there is provided a boss 89 having an opening 90, which boss is preferably integrally formed with the carriage as by casting. The upper end of the opening 90 is provided with a resilient bushing 91, preferably of rubber, into which the sound tube 87 tightly fits. Fitted into the lower end of the opening 90 and extending downwardly therefrom through a laterally extending opening 92 in the platform 19 of the base 6, is a coupling member 93. The coupling member is secured to the boss 89 as by a pin 89'; it is provided with an enlarged diameter end portion 93' which fits about the inner end of the speaking tube 79, and which is secured to the speaking tube by a set screw 94.

When the handpiece 80 is inserted in the compartment 12 the speaking tube 79 coils itself about in the compartment 12 in a manner such as is shown in Fig. 2. Since the cover 4 is fitted closely to the opening 22 of the compartment 12 the handpiece 80 must lie substantially within the compartment 12 whenever the cover is closed. In the compartment 12 there is provided a support 95 for the handpiece 80 having a widened and arcuately shaped end portion 95' fitting the handpiece, as is shown in Figs. 1 and 2. The support 95 is movable between upper and lower positions and comprises right and left upwardly extending

5 arms 96 and 97 interconnected by a bail 98. The arm 96 passes through an opening 99 in the bottom 49 of the channel 48 and is pivoted by a pivot screw 100 to the left side of the intermediate standard 13 between this standard and the intermediate gear 35', the gear being spaced clear of the arm 96 by means of a boss 13'' on the left side of the extension 13', as is shown in Fig. 7. The left arm 97 lies to the left of the central portion 24' of the reenforcing rib 24 and is V-shaped, as is shown in Fig. 6; it is pivoted to the boss 67 of the standard 14, to the right of the aforementioned arm 65, by the pivot screw 68.

In order that an opening of the cover 4 will effect a movement, through the opening 22, of the support 95 from its lower supporting position within the compartment 12 to an upper supporting position, shown in Fig. 6, to render the handpiece 80 readily accessible, there is provided an arm 101 on the arm 65, which extends downwardly to the left of the arm 97. The arm 101 is coupled to the support 95 by means of a pin 102, carried by the arm 101, which engages a slot 103 that is provided in the arm 97 and curved in an arc about the pivot screw 68. By reason of this coupling the support 95 is swung in the same direction as the cover 4 with the opening and closing of the latter. The angular distance between the open and closed positions of the cover 4 is, however, greater than the angular distance between the upper and lower supporting positions of the support 95, respectively shown in full and in dash-dot lines in Fig. 6. The slot 103 however provides a lost motion between the cover 4 and support 95, which is equivalent to the difference in their angular travel.

When the support 95 reaches its upper supporting position it is restrained from moving downwardly therefrom, except as an incident of closing the cover 4, by means of a latch 104 pivoted by a pivot screw 105 on a boss 106 provided on the left side of the reenforcing rib 24'. In the opening of the cover 4 the bail 98 contacts an inclined face 107 on the latch 104 and slides thereover. When the bail has passed the face 107 the latch snaps upwardly against a stop pin 108, by reason of a tension spring 109 connected between a short arm 104' of the latch and a pin 110 on the rib 24, to restrict the support against downward movement. As the cover is closed the pin 102 first traverses the slot 103, but before this traversal is completed a cam face 111 on the arm 101 contacts a pin 112 on the latch 104 to cause the latch to be moved free of the bail 98, the support 95 then being free to move downwardly within the compartment 12.

In order that the motor 39 may start automatically as an incident of removing the handpiece 80 from the support while the support is in its upper supporting position, there is provided means for effecting an upward movement of the support, into an upward position shown in dash-dot lines in Fig. 6 and hereinafter called its non-supporting position, incidental to the removal of the handpiece 80 therefrom, and this movement of the support is adapted to place the motor 39 in operation. This means comprises a cantilever spring 113 secured to the arm 97 by pins 112. When the cover 4 is opened the front edge 101' of the arm 101 is brought to bear against the spring 113 and to impart an upward biasing to the support 95 such as will move the support into non-supporting position when the handpiece 80 is removed therefrom. The weight of the handpiece 80 is, however, sufficient to overcome the

upward biasing of the support 95 so that the support will always move downwardly into the upper one of its supporting positions as the handpiece 80 is placed thereon.

On the left side of the central portion 24' of the reenforcing rib 24 there is secured by the screws 114 a normally open control switch 115. This switch comprises a frame 116 of suitable insulating material, preferably of Bakelite, on which there are mounted front and back switch contact springs 117 and 118. These contact springs may be appropriately connected, as by a cable 119 leading from the frame 116 by way of the vent 120, into a power supply circuit (not shown) of the machine so that closing and opening of the switch will respectively cause the starting and stopping of the motor 39. Secured, as by riveting, to the back switch spring 118 is a downwardly extending arm 121. This arm lies immediately ahead of a cross pin 122 carried by the arm 97 of the support 95. When the support 95 moves upwardly into its non-supporting position the pin 122 contacts the arm 121 and moves the switch spring 118 forwardly to cause the closing of the control switch 115, and when the support 95 moves downwardly out of its non-supporting position the switch spring 118 is rendered free to move rearwardly, as by its own bias, to cause the opening of the control switch 115. Thus, the removal of the handpiece 80 from the support 95 is adapted to start the machine operation; whereas the mounting of the handpiece 80 on its support is adapted to stop the machine operation.

Although I have herein described and illustrated a particular embodiment of my invention, it will be understood that the same is subject to many changes and modifications without departing from the scope of my invention, which I undertake to express according to the following claims:

I claim:

1. In a structure comprising a cabinet and a phonograph within said cabinet having a sound-receiving device adapted to be grasped by the hand during the use of the phonograph, said cabinet having a compartment therein for storing said sound-receiving device during the non-use of the phonograph: the combination of a closeable and openable closure on said cabinet; a support within said compartment for said sound-receiving device, operatively connected with said closure to automatically move outwardly and inwardly of said compartment in response to the opening and closing of said closure; and means rendered effective by said closure in the opening of the same for causing the support to be moved upwardly upon a removal of the sound-receiving device therefrom.

2. In a structure comprising a cabinet and a phonograph within said cabinet having a record support, a translating device movable across said support and a sound-receiving device for said translating device adapted to be grasped by the hand during the use of the phonograph, said cabinet having a compartment therein beneath said phonograph for housing said sound-receiving device: the combination of a sound-conveying means for coupling said translating device with said sound-receiving device comprising a sound tube carried with said translating device in fixed relation thereto and extending down to said compartment, and a flexible tube in said compartment connected at one end to said sound tube and terminating at the other end into said sound-receiving device; a closure on said cabinet openable to expose said translating device and an interior portion of said compartment; and a support in said compartment for said sound-receiving device operatively connected with said closure and moved out of and into said compartment upon the opening and closing of said closure.

3. In a phonograph structure comprising a cabinet and a sound-receiving device adapted to be grasped by the hand during the use of the phonograph, said cabinet having a compartment therein for housing said receiving device during the non-use of the phonograph: the combination of a closure on said cabinet openable to expose an interior portion of said compartment; a support for said receiving device mounted for movement inwardly and outwardly of said compartment; a latch for holding said support in outward position; and means, operatively connecting said support and said latch with said closure, for moving said support outwardly and subjecting the same to the action of said latch upon opening said closure and for unlatching said support and moving the same within said compartment upon closing said closure.

4. In a structure including a cabinet and a phonograph housed therewith comprising a drive mechanism, an on-off control for said drive mechanism, a record-cooperating sound translating device and a sound tube coupled to said device having a handpiece on the outer end portion thereof: the combination of an openable closure on said cabinet; a support for said handpiece movable to place the handpiece into a lower storing position within said cabinet and into an upper operative position wherein the same is rendered exposed by the opening of said closure; a lost-motion coupling between said support and closure causing the support to be moved into upper and lower positions by the opening and closing of the closure; resilient means operatively interposed between said support and said closure to raise the support above its said upper operative position when the weight of said handpiece is relieved therefrom, said support partaking of the lost motion in said coupling when the same is so raised; and means, actuated by said support in the range of movement thereof above said upper operative position, for operating said on-off control into "on" and "off" positions.

5. In a phonograph structure comprising a cabinet and a sound-receiving device adapted to be grasped by the hand during the use of the phonograph, said cabinet having a compartment therein for housing said sound-receiving device during the non-use of the phonograph: the combination of a closure on said cabinet openable to expose an interior portion of said compartment; a support for said receiving device mounted for movement inwardly and outwardly of said compartment; a lost-motion connection between said closure and said support adapted to cause said support to be moved outwardly and inwardly of said compartment upon opening and closing said closure; a latch for holding said support in outward position; and means, actuated by said closure in the closing movement of the same through the range of the lost motion of said connection, for releasing said latch.
